United States Patent

Des. 237,125
Patented Oct. 14, 1975

237,125

BOTTLE DISPLAY STAND OR SIMILAR ARTICLE

Jerome A. Moss, 333 West End Ave.,
New York, N.Y. 10023

Filed Mar. 12, 1973, Ser. No. 340,442

Term of patent 14 years

Int. Cl. D6—04

U.S. Cl. D6—153

FIG.1

FIG.3

FIG. 1 is a front and left side perspective view of a bottle display stand or similar article showing my new design;

FIG. 2 is a right side elevational view; and

FIG. 3 is a rear elevational view.

I claim:

The ornamental design for a bottle display stand or similar article, substantially as shown.
